(57) **CLAIM**

The ornamental design for a combination of earphones and case, as shown and described.

DESCRIPTION

FIG. 1 is a top, front, and right side perspective view of a combination of earphones and case showing my new design; FIG. 2 is a top, front, and right side perspective view of the combination of earphones and case, shown with earphones inside case;

FIG. 3 is a top, front, and right side perspective view of the combination of earphones and case, shown in a closed configuration;

FIG. 4 is a front elevational view of FIG. 3;

FIG. 5 is a rear elevational view of FIG. 3;

FIG. 6 is a left side elevational view of FIG. 3;

FIG. 7 is a right side elevational view of FIG. 3;

FIG. 8 is a top plan view of FIG. 3;

FIG. 9 is a bottom plan view of FIG. 3;

FIG. 10 is a perspective view of earphones of the combination of earphones and case, shown separately to show aspects of the design that are not visible when combined;

FIG. 11 is a front elevational view of FIG. 10;

FIG. 12 is a rear elevational view of FIG. 10;

FIG. 13 is a left side elevational view of FIG. 10;

FIG. 14 is a right side elevational view of FIG. 10;

FIG. 15 is a top plan view of FIG. 10; and,

FIG. 16 is a bottom plan view of FIG. 10.

The broken lines in the drawings depict portions of the combination of earphones and case that form no part of the claimed design.

1 Claim, 16 Drawing Sheets
